8 Claims. (Cl. 28—58)

The present invention relates to the wet treatment of textile materials, particularly of material made of animal, plant or synthetic fibers which is rather voluminous and is subject to shrinking. The textile material is exposed in a tub or vat to the effects of the so-called fluid or liquor which circulates through the vat and can be reversed in direction. As a rule, the material in the form of skeins of yarn is placed upon horizontally disposed rods which are received on the so-called material carrier in suspended condition. A further rod placed into each lower loop of the skeins of yarn and fastened in the material carrier secures the suspended position of the skeins of yarn against the effects of the liquor flow.

The known material carriers of this type for receiving skeins of yarn are not usable if synthetic skeins of yarn of very voluminous character are to be dyed, for example, yarn of the type which is available on the market under the trade mark Orlon skein yarn. This material, when subjected to the so-called wetting, dyeing, or any similar wet treatment, is subject to shrinkage to an extent of between 75% and 80% of the original length of the skein.

The vat in which the treatment takes place is, as a rule, one of rectangular cross section provided with an intermediate wall for forming a separate mixing or heating chamber for the liquor and a material treating or dyeing chamber into which the material carrier is inserted and wherein the liquor is caused to circulate by means of known circulating assembly (propeller or the like).

In accordance with a principal object of the invention, a material carrier is provided including means for the relative adjustment of the upper and the lower rods to the particular rod distance required as determined by the reel length of the skeins of yarn used and by the extent of shrinkage of the material in the wet treatment.

The means mentioned are intended to make it possible to determine the changes of the rod distances by means of indicator scales when the material carrier is inside as well as outside of the vat. In this manner the synthetic yarn is protected to a considerable extent during the dyeing process and netting and felting is prevented. For dyeing normal material in which no considerable shrinkage takes place during the wet treatment, a predetermined yarn distance can be set even before stocking or loading the material carrier, or it is possible to adjust for a distance corresponding to the reel length, in which connection the skeins may have a small sag.

For dyeing of synthetic material in skein form, which must be subjected to a wetting or shrinking process before the actual dyeing, the procedure is such that in order to determine the required rod distance a shrinkage test is first made on a single skein of yarn. This reveals the exact extent of shrinkage of the material. The complete loading of the material carrier with the textile material is then carried out while taking into consideration the values of the degree of shrinkage which has been determined during the shrinkage test.

The wetting or shrinkage treatment may be carried out

only in a calm, boiling bath. The material with the material carrier must, under no circumstances, be taken out of the hot liquor during the shrinking and the dyeing operation. This requires that the rod distance must be set with reference to the results of the shrinkage test and that the tentative setting must be made before the material carrier is loaded. Any subsequent adjustments of the rod distance which might become necessary can then be made during the course of the wet treatment of the material on the loaded material carrier which has been placed into the vat. The design of the material carrier in accordance with the invention provides for making adjustments or corrections of the exact rod distance in a very simple manner for effecting the undisturbed execution of the shrinkage and the subsequent dyeing process.

In accordance with a further object of the invention the material carrier is of particular and advantageous construction. Adjusting means for the upper rods include threaded adjusting spindles which are disposed vertically along parallel oppositely disposed walls of the material carrier and are rotatable in synchronism from the top of the carrier by means of a crank drive. They are disposed to cooperate with wide carrier or supporting sections provided with supporting yokes for the yarn rods to receive the yarn and on being rotated to adjust the height thereof. The adjusting means for the lower group of rods comprise simple support bars or sections with supporting yokes to receive the rods and threaded pins for securing the sections in place in corresponding holes disposed at different heights along the oppositely disposed walls.

In accordance with the invention a scale can be provided for setting the required height of the upper rods along each side wall of the open front of the carrier. The upper edge of the adjustable supporting bars serves as the indicator. A further indicating scale to show the height of the upper rods can be provided in the head of the material carrier. By means of this scale the distance of the upper rods from the lower rods can be corrected after the material carrier is disposed in the vat.

For the purpose of securing the rods against sliding out of their yokes when the carrier has been loaded and when the direction of flow of the liquor is changed so that the liquor flows from the bottom to the top, it is necessary to lock the rods by means of transverse locking rods, which is accomplished in a simple and safe manner by sliding the locking rods into lugs which are provided in the walls of the carrier.

The material carrier is provided around the upper third of its space with a horizontally disposed perforated spacing plate which serves for distributing the liquor and onto the ends of which cover plates can be hung at the open sides of the material carrier for the protection of the foremost rows of yarn, which plates may be locked into place along the vertical side sections of the material carrier by latching means of any known type, using a key of polygonal cross section.

In accordance with a further object of the invention the oppositely disposed side walls of the material carrier are inwardly offset along the lower third part thereof and provided in that area with the adjustable carrier bars or sections which support the yokes for the lower rods. Along the upper portion of these walls in the area corresponding to the offset part the threaded adjusting spindles are located. Threaded sleeves are provided, by means of which the carrier bars or sections for the upper rods are secured to the threaded spindles in a manner that the spindles upon being rotated carry these bars upwardly or downwardly, depending on the direction of rotation.

Other objects and advantages of the invention will become apparent from the following specification with reference to the accompanying drawing which illustrates a

material carrier in accordance with the invention and in which:

Fig. 1 is a plan view of the material carrier;

Fig. 2 is a side elevational view partly in vertical cross section taken from the left along line II—II in Fig. 1;

Fig. 3 is a vertical cross section taken along the line III—III in Fig. 1;

Fig. 4 illustrates one of the adjusting spindles to an enlarged scale as compared to Fig. 2;

Fig. 5 shows a yarn rod end to an enlarged scale;

Fig. 6 illustrates the center cross section of the yarn rod;

Fig. 7 is a plan view of the upper indicating scale drawn to an enlarged scale as compared to Fig. 1;

Fig. 8 is a section of the scale shown in Fig. 7 taken along line VIII—VIII;

Fig. 9 illustrates in a sectional view similar to Fig. 3 a vat including the dye fluid or liquor circulating assembly with a material carrier placed therein, and

Fig. 10 is a plan view of the apparatus in accordance with Fig. 9.

The material carrier which is a frame-like structure of generally rectangular cross-section is constituted essentially of two side walls 1 which are disposed parallel and opposite to one another and which are connected with one another at their lower ends by two oppositely disposed transverse struts 2. One of the transverse struts is suitably removably connected with the side walls to permit supplying the material carrier more conveniently with the fiber material which is to be treated and which is indicated in Figs. 2 and 3 as being in the form of suspended skeins of yarn. Approximately in the upper third between walls 1 and 2 a perforated sheet of metal 3 is mounted for the distribution of the fluid or liquor. When the material carrier is placed into the vat *a* (see Fig. 9) this sheet is located at the height of an intermediate overflow wall *b* of the vat. Walls 1 are connected at their upper ends with transverse members and a cover plate 4. At the lower third of their area walls 1 are offset inwardly toward each other at 1'. The offset location 1' provides space for mounting bearings. Below the perforated metal sheet 3 in the upper part of the material carrier, a yarn rod carrying bar 5 is located on each side 1, which bars are adjustable in height and which are connected with vertical threaded adjusting spindles 6, journaled at the bottom in bearings provided on the offset portions of the side walls for adjusting the height by rotating the spindles simultaneously. The yarn rod carrier bars 5 are each provided with two rows of yarn rod yokes 7 disposed in two rows above one another and which are provided to receive the upper horizontal bars 8 for suspending the skeins of yarn and which are disposed in staggered relation to each other. The yarn rods are formed in the manner indicated in Figs. 5 and 6. They are hollow rods which, as seen in Fig. 5, are of somewhat reduced diameter at their ends and which in this location define a closed shell formed by a welded seam 8'. Fig. 6 shows a section through the yarn rod 8 at any position intermediate its two ends. The edges of the yarn rod are turned over or beaded along one side in a manner that between the beads a slot 8" is formed which extends longitudinally of the yarn rod. A series of flow-off apertures is provided in the shell along the side opposite the slot.

In the lower third of the walls 1, i.e. below the offset locations 1', there is located between walls 1 a further support bar for the yarn rod yokes 9 which in a manner analogous to that shown at 7 are arranged in two rows, one above the other, and staggered with respect to one another and receive the lower yarn rods 10. This support with the yokes 9 is adjustable in height and is provided with threaded setting pins or set screws (not shown). It is possible by means of the latter to connect the support at the different heights with the walls 1.

The adjusting spindles 6 which are journaled proximate

their upper ends closely below the metal cover 4 are provided in pairs on each wall 1 at equal distances from one another and support each at their end above the cover plate 4, through which they extend, a bevel gear 13 which meshes with corresponding bevel gears mounted on shafts 12 provided with cranks 11. The synchronous operation of the crank shafts 12 and thus of the spindles 6 is insured by means of a chain drive 12'. By turning the crank shafts 12 the spindles 6 are rotated, and depending upon the direction of rotation the threaded guide sleeves 14 are adjusted upwardly or downwardly together with the yarn rod support bars 5 to which they are securely fastened against axial displacement, and movement causes increase or decrease in the distance between rods 8 and 10. One of the yarn rod support bars 5 may be used to serve as an indicator for the adjusted position of the support bars 5 in a manner that the location of the indicator means can be read on a scale 15 provided on the side wall 1.

Supporting lugs 17 are provided on support bars 5 into which locking rods 16 may be inserted in a manner that the yarn rods 10 are firmly positioned upon loading the material carrier.

Cover plates 18 are provided along the open sides of the material carrier which, after the loading, protect the material against damage and smudging. In order to make it possible to remove the plates readily, they are mounted by means of pins 19 in bores along the edge of perforated intermediate bottom 3 and secured, for example, by means of conventional latches 20.

An indicating device 21 is suitably coupled with one of the crank shafts 12 which is provided with a threaded portion, the indicator position of which can be read on a scale (see Figs. 7 and 8). The indicator is guided in a longitudinal slot of the scale support and in this manner is prevented from rotating so that it moves along the scale when shaft 12 is rotated. As indicated in Fig. 8, the threaded portion on shaft 12 is covered by a protector shield. This arrangement makes it possible to determine from above the particular adjusted distance between rods 8 and 10 from one another in the material carrier which has been placed into the tank or vat and to correct any inaccurate setting which is noted before the dyeing operation. In this manner an opportunity is provided, if after shrinking of the material the required sag needs adjustment, to lengthen or shorten the skeins of yarn as may be required for carrying out the dyeing operation, i.e. to compensate for or correct any difference which results from the shrinking process.

A device 22 is provided for hanging the material carrier into the vat *a* or for removing it therefrom. At the head of the material carrier, rails 23 are provided which present at their free ends recesses for engagement by securing members on the vat *a* (not illustrated), by means of which the material carrier is fastened in the vat.

It is not absolutely necessary to provide at the upper end carrier 5 and the lower rod carrier several rows of rods at different heights because it is possible at any rate to adjust to each reel length between about 1640' and 2790'.

Instead of providing two threaded adjusting spindles 6 along each side wall 1 with two cranks 12 at the head, it is possible for small capacity requirements to provide only a single spindle along each wall together with a crank, in which case additional provisions must be made, however, to prevent the rod carriers 5 from becoming wedged in or bent during their movement.

The lower yarn bar yokes 9 could also be mounted permanently on the walls 1 instead of being adjustable, in which event additional rows would have to be provided. The essential point is that a relative adjustment is possible between the upper and the lower rows of rods.

The skein material to be dyed or subjected to any other wet treatment is supplied onto the yarn rods in the manner indicated after they have been set for the re-

quired yarn a distance depending on the working operation and on the reel length. With normal material to be dyed without a shrinking process, it is possible to do this in that the distance of the upper edge of the upper yarn rod to the lower edge of the lower yarn rod is adjusted by approximately a hand width less than the clear reel length of the yarn material to be dyed. However, with yarn which shrinks considerably during wet treatment, such as the materials known under the name nylon and the trademark Orlon, greater sagging of the material before dyeing is necessary in order not to prevent the material from shrinking. For this reason the operation with the last mentioned combined shrinking and dyeing process involves only the lower yarn rods mounted in the higher positions.

The vat *a* which is not a part of the subject of the application is provided with a liquid intake *c* and a liquid drain *d*. A motor at *e* moves a propeller in a manner that the treatment liquor takes the course indicated between arrows in Fig. 9. A heating assembly *f* is mounted in the path of the liquor ahead of the overflow *b* which may be supplied with steam through a supply stub *g* and an outlet stub *h*.

Having now described our invention with reference to the embodiment illustrated in the accompanying drawings, we do not wish to be limited thereto, but what we desire to protect by Letters Patent of the United States is set forth in the appended claims.

We claim:

1. A material carrier for the treatment of voluminous shrinkable and non-shrinking fibrous material in a vat provided with a reversible liquor circulating system, said carrier being adapted to be received in said vat and being generally in the form of a frame arranged to receive skeins of the fibrous material suspended in reel length upon rods, said carrier comprising upper rods horizontally disposed in said frame for supporting the upper loops of the skeins and lower horizontally disposed rods extending through the lower loops of said skeins in a manner to maintain the suspended position of said skeins during circulation of the liquor, means for supporting said upper rods in said carrier, means for supporting said lower rods in said carrier and adjusting means including vertical members extending endwise of said rods operative in synchronism to establish the relative distance of said upper and lower rods with respect to each other as determined by the reel length of said skeins and by the shrinkage of the fibrous material, and indicator means operatively related to said adjusting means and movable in synchronism with said vertical members disposed to indicate the variations in the distances between the rods while said carrier is disposed within and outside of said vat.

2. A material carrier for the treatment of voluminous shrinkable and non-shrinking fibrous material in a vat provided with a reversible liquor circulating system, said carrier being adapted to be received in said vat and being generally in the form of a frame arranged to receive skeins of the fibrous material suspended in reel length upon rods, said carrier comprising upper rods horizontally disposed in said frame for supporting the upper loops of the skeins and lower horizontally disposed rods extending through the lower loops of the skeins in a manner to maintain the suspended position of the skeins during circulation of the liquor, means for supporting said upper rods in said carrier, means for supporting said lower rods in said carrier and adjusting means operative to establish the relative distance of said upper and lower rods with respect to each other as determined by the reel length of the skeins and by the shrinkage of the fibrous material, and indicator means operatively related to said adjusting means and disposed to indicate the variations in the distances between the rods while said carrier is disposed within and outside of said vat, said carrier comprising opposite side walls, said means for supporting said upper rods extending horizontally and parallel to said side walls, said adjusting means including at least one threaded spindle in operative engagement with said means supporting said upper rods disposed vertically in said carrier proximate said opposite side walls, a crank being disposed in operative relationship endwise of one said spindle on one said side wall, and said means for supporting said lower rods including yokes adapted to receive said rods and members having conformations adapted to interlock with corresponding conformations in said side walls to secure said supporting means in different positions of height in said carrier.

parallel to said side walls, said adjusting means including threaded spindles in operative engagement with said means supporting said upper rods disposed vertically in said carrier proximate said opposite side walls, a crank being disposed in operative relationship endwise of each spindle, said spindles being linked to each other to provide for synchronous operation, and said means for supporting said lower rods including yokes adapted to receive said rods and members having conformations adapted to interlock with corresponding conformations in said side walls to secure said supporting means in different positions of height in said carrier.

3. A material carrier in accordance with claim 2, wherein an indicator scale is provided on one of said side walls and said means supporting said upper rods includes a pointer extending from said side wall to indicate the position of said rods in said carrier.

4. A material carrier in accordance with claim 2, wherein said vertical spindles proximate said opposite side walls are operatively connected by horizontally disposed spindles and said indicator means include a device operatively connected to one of said horizontally disposed spindles.

5. A material carrier in accordance with claim 2, wherein bars are provided extending transversely of said rods and means securing said bars to said supporting means for said rods.

6. A material carrier in accordance with claim 2, wherein said opposite side walls are offset inwardly and horizontally proximate the lower portion thereof providing bearing shoulders for the lower ends of said spindles.

7. A material carrier for the treatment of voluminous shrinkable and non-shrinking fibrous material in a vat provided with a reversible liquor circulating system, said carrier being adapted to be received in said vat and being generally in the form of a frame arranged to receive skeins of the fibrous material suspended in reel length upon rods, said carrier comprising upper rods horizontally disposed in said frame for supporting the upper loops of the skeins and lower horizontally disposed rods extending through the lower loops of the skeins in a manner to maintain the suspended position of the skeins during circulation of the liquor, means for supporting said upper rods in said carrier, means for supporting said lower rods in said carrier and adjusting means operative to establish the relative distance of said upper and lower rods with respect to each other as determined by the reel length of the skeins and by the shrinkage of the fibrous material, and indicator means operatively related to said adjusting means and disposed to indicate the variations in the distances between the rods while said carrier is disposed within and outside of said vat, said carrier comprising opposite side walls, said means for supporting said upper rods extending horizontally and parallel to said side walls, said adjusting means including at least one threaded spindle in operative engagement with said means supporting said upper rods disposed vertically in said carrier proximate said opposite side walls, a crank being disposed in operative relationship endwise of one said spindle on one said side wall, and said means for supporting said lower rods including yokes adapted to receive said rods and members having conformations adapted to interlock with corresponding conformations in said side walls to secure said supporting means in different positions of height in said carrier.

8. A material carrier for the treatment of voluminous shrinkable and non-shrinking fibrous material in a vat provided with a reversible liquor circulating system, said carrier being adapted to be received in said vat and being generally in the form of a frame arranged to receive skeins of the fibrous material suspended in reel length upon rods, said carrier comprising upper rods horizontally disposed in said frame for supporting the upper loops of the skeins and lower horizontally disposed rods extending through the lower loops of said skeins in a manner

to maintain the suspended position of said skeins during circulation of the liquor, means for supporting said upper rods in said carrier, means for supporting said lower rods in said carrier and adjusting means including vertical members extending endwise of said rods operative in synchronism to establish the relative distance of said upper and lower rods with respect to each other as determined by the reel length of said skeins and by the shrinkage of the fibrous material, indicator means operatively related to said adjusting means and movable in synchronism with said vertical members disposed to indicate

the variations in the distances between the rods while said carrier is disposed within and outside of said vat, and a perforated liquor distributing plate disposed horizontally in the upper portion of said carrier.
